UNITED STATES PATENT OFFICE

2,470,302

GAME BOARD AND APPARATUS

Frederick E. Green, Spokane, Wash.

Application November 24, 1947, Serial No. 787,662

1 Claim. (Cl. 273—87)

1

My present invention relates to an improved game board and apparatus of the type herein shown as designed for simulated golf, the various holes being laid off pictorially and formed with cups. The game is played by locating the relatively small ball at the tee position and the player by exhaling through a straw or similar tubular guide and properly directing the straw, may project the ball from the tee toward the green and the cup. Suitable hazards and obstacles are supplied to render more difficult the play, and the score is kept by counting the number of "strokes" required to move the ball from a tee to a cup.

In the accompanying drawings I have illustrated one complete example of the physical embodiment of my invention according to the best mode I have thus far devised, but it will be understood that various changes and alterations may be made in the exemplified structure within the scope of the appended claim, to include foot-ball, basket-ball, baseball or other games or sports which may be played in a similar manner.

In the drawings:

Fig. 1 is a perspective view of the game board.
Fig. 2 is a vertical sectional view.

Fig. 3 is a bracketed view of the straw and ball.

Referring now to the drawings wherein I have illustrated the present preferred embodiment of my invention, I employ a game board 2 of plane material having side wall 4. A layer of suitable material 6 is laid upon the board and formed with pictorial illustrations of tees 8, and fairways 10 leading to greens 12.

The tees are provided with a recess or depression 14 to receive the ball, and the greens have a recess or cup 16 to receive and retain the played ball.

Various other hazards or obstacles may be employed off the fairways and consisting of irregularly shaped recesses 18 having beveled walls 20, some having the bottoms covered with sand paper 22, and others with metal foil 24 to simulate sand traps and water hazards, respectively.

As further hazards I employ the objects 26 preferably of wood to simulate trees, and the arched bridge 28 and tunnels 30 will add to the need for skill and enhance the pleasure of the game.

2

A ball 32 of suitable size, shape and material is located in the tee depression 14 and the player using the hollow straw tube 34 blows through the tube against the ball to force the ball out of the depression and toward the green at the end of that fairway.

With the playing surface flat the ball if properly projected may run true and fall into the cup 16. However should it be not projected true, 10 it will roll off the fairway and into a hazard from which it must be further projected.

A beveled trough 36 around the periphery of the playing surface will retain a ball rolling therein and may be determined as out of bounds.

Obviously the game may be employed to simulate other pastimes such as basketball, football, tennis and the like and such games would normally require two or more players whereas the simulated golf game may be played by one person.

Having thus fully described my invention what I claim as new and desire to secure by Letters Patent is:

A game board for simulated golf games comprising a base board, an upper board layer superimposed upon the base board and having irregularly shaped openings therein, layers of sand-coated material under some openings and layers of smooth metal foil under other openings, the 25 walls of said opening being beveled, and said upper board having shallow ball-receiving depressions at the tees, and deeper ball-receiving depressions at the greens, and an enclosing wall about the game board.
